DOUBLE ACTION SPINNING AND
TWISTING FRAME

Walter Cox, Methuen, and Gardner W. Pearson,
Lowell, Mass., assignors to Rox Supply Co.,
Lowell, Mass., a corporation of Massachusetts

Application January 26, 1933, Serial No. 653,572

4 Claims. (Cl. 118—54)

This invention relates to what are known in the textile trade as ring spinning or twisting frames.

As a rule, cotton spinning is performed on a frame in which there are what are known as

5 Rabbeth spindles which stand up vertically and revolve in suitable bearings, but do not move axially. Bobbins are fixed on them and revolve each bobbin on and with its spindle. Cooperating with these spindles and bobbins is a ring 10 rail carrying spinning rings, the ring rail being caused to move so that the center of each ring moves up and down along the axis of a spindle and of a bobbin.

When starting to build a bobbin, the ring rail 15 is dropped to the lowest point opposite the head of the bobbin and if a warp wind is desired the rail with its rings is caused to move up and down the length desired thus building concentric cylinders of yarn.

20 If a filling wind is desired the ring rail is caused to traverse or reciprocate up and down gaining at each successive reciprocation so that a filling wind consisting of concentric cones instead of cylinders of yarn is formed.

25 On a cap spinning frame, such as used formerly for worsted, there are fixed guide rods which are not tapered but are cylindrical and which are improperly called spindles. These are fixed to what is known as a spindle rail and neither

30 move axially nor do they revolve. Each carries at the top, however, a cap around the lower rim of which the roving is delivered and spun on a bobbin which revolves partly inside and partly outside the cap.

35 Each bobbin is carried on a tube having a whirl, the carrier and bobbin being caused to revolve on the guide rod or spindle and also caused to traverse or reciprocate starting with the head about opposite the bottom rim of the 40 cap and moving down and then up for a warp wind or reciprocating or traversing downward gaining after each reciprocation if a filling wind is desired.

45 It has been proposed to move both the ring and a movable spindle either at the same time in opposite directions or with different movements according to the result desired.

An application for patent on Reciprocating 50 bobbins ring frame to cause the ring rail to move in a direction at all times opposite to that of the bobbin has been filed by Walter Cox and became Patent No. 1,998,981, April 16, 1935, and it has been proposed to cause the ring rail to 55 traverse or reciprocate progressively upward

while a revolving spindle is caused to move steadily downward without reciprocating.

For a great many years, it was not believed that worsted yarn could either be spun on a spinning frame or twisted on a twisting frame by the 5 use of rings and travellers, but now ring frames are used to some extent.

One advantage of the cap frame was that the distance from the edge of the cap to the pot eye and the delivery rolls was constant and the 10 conditions between those points, therefore always the same.

The serious objection, however, was the fact that the length of the yarn package was limited by the length of the cap and its diameter by the 15 diameter of the cap.

It has also been believed that worsted should be spun and twisted on a bobbin having a cylindrical barrel and a head which was at right angles to the barrel and that the space between 20 them should be filled by the use of a scaife or other similar builder motion which would start with a short traverse the length of which would gradually increase caused by the dropping of the bobbin, until the desired maximum was reached 25 after which the bobbin would traverse progressively downward thus building successive cones in a well known manner provided a filling wind was desired.

The tendency among spinners and twisters of 30 late years is to use the filling wind to the exclusion of the warp wind because each concentric cone appears at the surface and if there is any flaw in the yarn, it can be readily detected while with the warp wind, nothing but the outside 35 layer shows and there may be many defects on the inside layers.

In what has been known and is known as the cotton ring frame, the bobbin revolves, but does not move axially, but the ring starts near the 40 head of the bobbin and reciprocates progressively upward. This means that, as each layer is built, the distance from the delivery rolls or guide eye through the traveller to the bobbin barrel or to the outside of the yarn package 45 repeatedly varies and the tension likewise varies.

It is well known among spinners that on this type of frame only small packages can be built because, on account of the change in tension, the 50 roving breaks.

On the other hand, with the cap frame or where a stationary ring replaces the cap, and the bobbin reciprocates downward, while the distance from the traveller to the barrel or to the nose of each layer is greater than to the out- 55

side of the layer, the distance from the traveller to the guide eye and feed rolls does not vary.

Too many reciprocations of the ring rail, causing variations in the tension, is objectionable as are also reciprocations of too great length for the same reason.

In this device, the ring rail is caused to move steadily upward while at the same time the bobbin revolves and is caused by the usual scaife motion to reciprocate progressively downward on a fixed spindle. In the usual operation of the scaife motion, the bobbin starts with a very short reciprocation which gradually increases to the maximum, and this short reciprocation, when the frame starts, avoids the rapid changes in tension produced by certain other motions and there are, therefore, fewer breaks.

With this construction we maintain the advantage of having the bobbin reciprocate progressively downward, preferably starting with the short reciprocation as in the cap frame, while maintaining substantially the advantage of the relatively stationary or fixed lower rim of the cap, or a ring, and also, by moving the ring, which amounts to a delivery point, gradually upward, a longer bobbin or yarn package can be wound and, at the same time, doffing is made easier because at the top end of the yarn package the rings are in the extreme up position, thus allowing the bobbin with its yarn to be more readily doffed. This upward movement of the ring rail is so gradual and continuous or of the step by step type that the variation in the distance from the guide eye to the ring does not tend to stretch nor to break the roving.

We show different mechanism for producing the preferred motion which is to move the bobbin reciprocally and progressively downward and the ring steadily or step by step upward but there are other mechanisms which could be utilized for producing this result and other results which may be useful in some cases.

For instance, the scaife motion may be set for a constant reciprocation of the bobbin rail, each reciprocation being of the same length and in the same position, while the ring rail moves steadily upward thus building concentric or overlapping layers of yarn which are not precisely of cone shape but produce a yarn package of well known or pointed at both ends.

It is well known that many breaks occur when starting the frame and that breaks occur in a ring frame when the ring changes its direction. With the combination of the scaife motion acting on the bobbin and a gradual upward movement, which is not reciprocal, for the ring, a much better action is obtained than where the ring itself reciprocates the full traverse progressively upward.

It is better to give the ring rail a very slow steady upward movement which is neither reciprocal nor intermittent so that there will be no tightening nor loosening of the yarn or roving, because when the movement is intermittent or reciprocal, more breaks occur.

Some means must be provided for bringing back the ring rail and the bobbins to the starting position. Preferably this should be accomplished from one end of the frame by disconnecting the drive mechanism and turning back all the parts, but this resetting can be accomplished in various ways as by turning the usual hand wheel thus raising the bobbin rail and then by other means causing the ring rail to drop to the starting point.

With the preferred construction, while the bob-

bins reciprocate and may move progressively downward, the ring rail can be caused to move steadily upward without reciprocating, the ring rail can be fixed at any desired height, or the ring rail can be caused to reciprocate progressively upward oppositely from and caused by the movement of the bobbin rail as it reciprocates progressively downward. It is, therefore, very flexible and adjustable.

In the drawings, Fig. 1 is an elevation at one end from the front of a spinning frame embodying this invention.

Fig. 2 is an enlarged elevation from the front showing the operation of the gears and hand wheel which operate the motion screw.

Fig. 3 is an elevation as from the left of Fig. 1 showing the sprockets and driving mechanism.

Fig. 4 is an enlarged elevation showing the operation of one type of lifting lever.

Fig. 5 is a section from the left of line 5—5 of Fig. 4.

Fig. 6 is a vertical sectional elevation of a supporting rail, rod guide or spindle, bobbin rail, bobbin and ring with the outlines of a yarn package as built by one adjustment of a scaife motion.

Fig. 7 is a plan view of Fig. 3 on a somewhat enlarged scale.

Fig. 8 is a detail elevation showing one arrangement of the pivot for a lifting lever.

Fig. 9 is an elevation showing another adjustment of the lifting lever shown in Fig. 1.

Fig. 10 is a view similar to Fig. 9 of another type of lifting lever.

Fig. 11 shows diagrammatically the difference in the movements of the bobbin and the ring when the device is set to build a yarn package of the shape shown by the dotted lines in Fig. 6.

Fig. 12 shows the shape of a yarn package made when the movements of the bobbin and ring are caused to be as shown diagrammatically in Fig. 13.

Fig. 14 is a detail elevation showing an alternative arrangement of the parts with no lifting lever.

Fig. 15 shows a modification of the arrangement shown in Fig. 14 where the lifting lever is omitted.

Fig. 16 is a front elevation and Fig. 17 is an end elevation of a system of gearing which can be used to take the place of the chain and sprocket constructions shown in Figs. 1, 2 and 3.

Fig. 18 is a front elevation of another arrangement of parts to produce the desired motion of the ring rail.

Fig. 19 is a sectional view of Fig. 18 as from the left on the line 19—19.

Fig. 20 is a view similar to Fig. 18 showing the parts in a somewhat different position.

In the drawings, F represents a fixed frame and 10 represents a fixed spindle rail or guide rod rail from which upwardly project a plurality of guide rods R, R each of substantially cylindrical form and of a well known type.

Slidable and revolute on each rod R is a bobbin holder H each of which is provided with a whirl 11 driven by a band or belt 12 as from a drive roller 13. Each bobbin holder H carries a suitable bobbin B having a barrel 1 and head 2 of any well known type.

1 represents a bobbin rail upon which each of the holders H rests and S represents a builder motion the one shown being of the well known scaife type. As shown, this includes a lifter bar 20 from which extend chains 21 over pulleys 22.

each one connecting to the bottom of a lifter rod 23 which slides in suitable guides up and down. These lifter rods carry the bobbin rail A.

The lifter bar 20 is caused to move by what is known as the motion screw 24 which passes through the motion nut 25 carried at the end of the long lever 26 which is pivoted at 27 to the frame.

The shank 28 of the motion screw has a lengthwise keyway 29 which engages a key 30 in a hub 31 which carries a gear 32 and a hand wheel 33, gear 32 being revolved usually by a connecting gear 34 driven by a drive gear 35.

36 is a lock of the usual construction which holds the gears 32 and 34 together during the usual operation of the frame. However, when it is desired to turn back the parts, lock 36 is disengaged and wheel 33 is pulled out, as shown by the dotted lines Fig. 1 thus allowing the motion screw to be turned back in the motion nut bringing the parts back to their original positions.

37 is the monkey adjustable on the long lever and 38 is the short lever with which it cooperates motion being given the short lever by the heart 39.

40, 40 represent the lifter rods for the ring rail C carrying rings 41, 41 each having a traveller 42, these lifter rods passing through suitable guides so that they can move up and down carrying with them the ring rail C. On each rod 40 is an adjustable button 44, the position of which can be adjusted as by a set screw 45.

46, 46 represent suitable pivot supports each carried by a lower rail W and each pivotally supporting a lifting lever L of the bell crank type. This is shown as pivoted at 50 and with one arm 51 of the forked type which extends around a rod 49 underneath the adjustable button 44, the other arm 52 being bent at 53 and extending down and in front of another adjustable button 54 on a flexible lifter cable T which is connected with the special mechanism U, all transmitting motion from the scaife motion S to the ring rail C with its rings.

This cable T extends along the front of the frame and, as shown, is connected by means of a spring 55 with the other end of the frame and is shown as being supported by suitable guides 56 so that at all times it will remain straight and taut. It extends around a pulley 57 and from there is wound upon a barrel 60 of a sprocket 61 which is connected by a chain 62 with a small sprocket 63 carried by the hub of a large sprocket 64 from which extends a chain 65 to another sprocket 66 carried by the hub 31 of the hand wheel 33 for the motion screw.

It is obvious that the reciprocating movement of the motion screw produced by the heart 39 through the short and long levers will not be transmitted through the mechanism U and T to the ring rail but the revolving of the motion screw and the wheel 33 through the sprocket 66 while being greatly reduced in extent will be so transmitted that rope T will be gradually wound up on hub 60.

The result of the winding up of the rope T will be, if the adjustable members 54 and 44 are properly adjusted with reference to their cooperating lever L, in the ring rail being moved steadily and not reciprocally upward as the bobbins move reciprocally or progressively downward.

Adjustable member 54, shown as a collar, can be fixed in any position on the cable T, which we might call a pulling member, as by means of a set screw 154 and adjustable button 44 can be

adjusted in any position on ring rail lifter rod 40 by means of set screw 45. The result of this is that by suitable adjustments the ring rail can be started in an upward movement, as shown diagrammatically in Fig. 11, from X to Y or this action can be delayed until towards the end of the yarn package which is being built on the bobbin.

If the ring rail is to move steadily upward and the bobbin rail with bobbin and holder to move reciprocally or to traverse progressively downward starting at the same time, the diagram in Fig. 11 shows what happens. In other words, the ring rail starts going up from X to Y at the same time that the bobbin starts going down from X to Z.

Starting with the ring rail C carried by vertically slidable ring rail rods 40 and the bobbin rail A carried by vertically slidable bobbin rail rods 23, it is possible and sometimes desirable to provide several different movements respectively to adapt the frame for different types of stock.

The scaife motion, shown at S, is what might be called a universal builder motion because by suitable adjustments a filling wind, a warp wind or any other well known wind can be produced on a bobbin. For a spool or warp wind, the monkey 37 can be dropped to its lowest limit and the connecting gear 34 can be removed whereby the motion screw 24 ceases to revolve but does reciprocate.

By a very slight change in the construction and by combining to some extent with the construction shown in application on Reciprocating bobbin ring frame, Serial No. 425,867 filed February 4, 1930 by Walter Cox, one of the applicants for this Letters Patent, it is possible to change the relative motions of ring rail and bobbin rail if desired.

In Fig. 8 there is shown a pivot stand 46 carried by rail W with a vertical series of holes 70, 70, the same as shown in Fig. 1. A pin 50 passed through any one of these holes and through a suitable hole such as 47 in the part 150 of lever L or a similar hole in a lever M serves as a vertically adjustable pivot for such a lifting lever.

In either case by removing pin 50, the lever such as L or M can be entirely removed and the ring rail C thereby adjusted at any desired height by loosening the set screw 45 and moving the button 44 down until it rests on rail W, when by tightening the set screw it holds the ring rail in any desired position as shown in Fig. 9.

If the reciprocal action of ring rail and bobbin rail is desired, a lever such as M pivoted at 70 with an arm 73 extending under a button 4 adjustable by a set screw 75 on bobbin rail rod 23 and another arm 71 extending under the button 44 adjustable by a set screw 45 on ring rail rod 40 is used.

The adjustable member 54 on pulling member 60 T is moved over to the right out of the way and the buttons 4 and 44 are so adjusted that the movements of the bobbin rail rod 23 caused by the builder motion S are transmitted to the ring rail by its rods 40 whereby a reciprocal movement in opposite directions is given the ring rail and the bobbin rail.

With this type of lever M, an additional arm 72 corresponding with arm 52 can be fixed to arm 73 in such position that it can be engaged by the adjustable member 54, as shown in Fig. 4 and the button 4 can be moved up out of the way to the full line position shown in that view. With this type of three armed rocking lever and the means such as the pin 50 to pull it out of action, with-

out any other changes the bobbin rail and ring rail can be reciprocally moved, the ring rail can be fixed in any desired adjusted position or the bobbin rail can be caused to reciprocate or traverse progressively downward while the ring rail is caused to move steadily upward.

There are various other ways by which the reciprocating and downwardly progressive movement of the bobbin rail can be converted into a steadily upward movement of the ring rail.

As shown in Fig. 14 the lifting lever can be dispensed with and a flexible member such as a chain 76 can be passed over a pulley such as 77 one end being fastened to an adjustable member 54 and the other end to a bracket 78 attached to the bottom of a ring rail rod 40.

The horizontal movements of the pulling member T are, therefore, transformed into similar vertical movements of the ring rail and its rods.

Instead of a continuous member like 76 and a single pulley 77, as shown in Fig. 15, a pulley 174 with a hub 175 can be used.

A member 176 is attached to the rim 177 at one end and to 54 at the other end while the member 178 extends from the hub 175 down to a member like 78. With this arrangement, the movement of member T can be reduced or if the member 176 is connected to the hub and 178 to the rail, the movement can be increased at will.

Another method of transmitting the motion is shown in Fig. 10 by a modified lever N pivoted at 170 to spindle rail 10 and having a short arm 171 which extends under button 44 and a long arm 172 which extends down and in front of adjustable member 54.

In this way, the movement of member T is reduced so that the movement of the ring rail is less.

As shown in Figs. 16 and 17 instead of using a sprocket such as 66 carried by the hub 31, a gear 160 which is longer than gear 32 on hub 31 also engages a gear 164, of much larger size, with a small hub gear 163 which engages another gear 161 with a small hub 167 on which is wound the end of pulling member T. The purpose of this long gear 160 is to permit the motion screw and its hand wheel 33 to be pulled out, as shown by the dotted lines in Fig. 16, for the purpose of winding up or moving up the bobbin rail when starting the winding of a new set of bobbins after doffing.

In Figs. 18, 19 and 20 is shown still another method of transforming the downwardly progressive reciprocal motion of the bobbin rail into an upwardly steady movement of the ring rail.

To the lifter bar 20 is adjustably fastened a finger 90 in such position that when the frame is started it will just strike and move slightly an arm such as 91 fixed to a ratchet wheel 92 carried by a suitable shaft 93 in bearings 94 on the rail W such shaft also carrying a cam 95.

The two pawls 97a and 97 prevent the ratchet wheel 92 from turning back and these may be arranged in such positions that first one takes hold of a tooth and then the other, the space being such that the idle one will rest between two teeth on the wheel 92. The cam 95 engages a lever 96 which is pivoted at one end to any suitable part of the frame and at the other end connects with a flexible member 197 which runs up and over a horizontal shaft 98 which extends from one end of the frame to the other. The movement of cam 95 forces down the free end of lever 96 thereby turning the shaft 98 in the direction of the arrow. Another flexible member 99

is fastened to shaft 98 and extends in a direction opposite to 197 and is connected to a suitable bracket 100 similar to bracket 78 at the bottom of ring rail rod 40.

The result of this is that as the finger 90 moves reciprocally and gradually gaining toward the left as the motion screw is unscrewed, ratchet 92 is slowly turned carrying with it cam 95 and depressing lever 96 thus turning shaft 98 and lifting the ring rail, through 99, which is shown as fastened to a pulley 199 and passing over loose pulley 202. Set screws 201 and 203 permit the adjustment of 198 and 199.

The holes 196 in lever 96 permit a different adjustment of flexible member 197 whereby a greater or less turning movement can be given shaft 98. The holding pulley 198 can be moved along shaft 98 to accommodate 197.

193 is a resetting handle to be used when returning the ring rail to its starting point by turning the cam 95 so that its low part will engage lever 96 thus permitting the weight of the ring rail and other parts to return them to the starting position. When resetting, the pawls 97, 97a are thrown out of engagement with the ratchet 92, as shown in Fig. 18, the cam is turned as stated, the hand wheel 33 is pulled out disengaging gears 34 and 32 and the motion screw is turned in the usual way thereby lifting the bobbin rail with its bobbins to the starting position.

It is obvious with this mechanism that if the pawls 97 and 97a are thrown out, the ring rail can be retained in top adjusted position while the bobbin will travel reciprocally downward in the usual manner.

The ring rail and all its operating parts can be held in the top or up position by pushing a pin 110 through holes 111 and 112 thus holding arm 91 out of contact with finger 90.

If pawls 97 and 97a are thrown out and pin 110 is not used, arm 91 will transmit to the ring rail from finger 90, the reciprocal progressive movement given rod 20 by the builder motion, but in the opposite direction.

We claim:

1. The combination in a spinning or twisting machine having a fixed frame, a fixed spindle rail with fixed guide rods extending up vertically therefrom, bobbin holders each revoluble and slidably on a guide rod and supported on a bobbin rail, means to revolve the bobbin holders, a builder motion to cause the bobbin rail, holders and bobbins to reciprocate progressively downward, the reciprocations increasing in length to a predetermined maximum after which they remain constant in length but move progressively downward, and revoluble means to operate the builder motion; a ring rail carrying rings and having supports which permit the rings to move with their centers each along the axis of a guide rod; and means connecting the revoluble means to operate the builder motion with the ring rail, whereby it moves steadily upward as the bobbin rail reciprocates progressively downward.

2. The combination in a spinning or twisting machine, of a fixed vertical guide rod with a bobbin holder slidable and revoluble thereon and a spinning ring movable with its center along the axis of the guide rod; of builder mechanism including a constantly revolving drive member, a motion screw revoluble with and slidable through a hub which is driven by the constantly revolving member but which is disengageable therefrom, a

winding barrel revoluble by the motion screw hub, connections from the winding drum to lifter rods which carry the ring, and connections between the motion screw and the bobbin whereby the bobbin is given a reciprocating motion progressively downward and the ring is given a non-reciprocating steadily upward movement.

3. In a machine of the character described and in combination, a ring rail having spinning rings thereon, a stationary guide rod rail having substantially cylindrical vertical guide rods extending upward therefrom each through the center of a ring; a bobbin holder and bobbin each revoluble and slidable on a guide rod; a builder motion capable of giving the bobbin rail trav-

erses progressively advancing downward; and means for moving the ring rail steadily and progressively upward during the progressive downward advance of the traverses of the bobbin rail.

4. The combination in a spinning or twisting machine including a fixed vertical guide rod; of a bobbin slidable and revoluble on said guide rod, and a spinning ring movable with its center along the axis of said guide rod; with builder mechanism to move the bobbin in traverses progressively downward and the ring steadily upward.
